US0D1075548S

(12) United States Design Patent (10) Patent No.: US D1,075,548 S
(45) Date of Patent:  May 20, 2025

(54) BRACELET

(71) Applicant: ARSIS JEWELRY CO., LIMITED,
Hong Kong (CN)

(72) Inventor: Hui Zhang, Beijing (CN)

(73) Assignee: ARSIS JEWELRY CO., LIMITED,
Hong Kong (HK)

() Term: 15 Years

(21) Appl. No.: 29/986,640

(22) Filed: Jan. 17, 2025

(51) LOC (15) Cl. 11-01

(52) U.S. Cl.
USPC D11/3

(58) Field of Classification Search

USPC D11/1-5, 26-34, 81-83, 96

CPC A44C 9/00; A44C 13/00
